[57] CLAIM

The ornamental design for a housing for connector of electric supplier for electric car, as shown and described.

DESCRIPTION

FIG. 1 is a perspective view of a housing for connector of electric supplier for electric car showing our new design with both the inner lid and outer lid closed;

FIG. 2 is a front elevational view thereof;

FIG. 3 is a rear elevational view thereof;

FIG. 4 is a top view thereof;

FIG. 5 is a bottom view thereof;

FIG. 6 is a left side view thereof;

FIG. 7 is a right side view thereof;

FIG. 8 is a front view in elevation with the inner and outer lids open and nested with each other;

FIG. 9 is a front view of the inner lid only;

FIG. 10 is a rear view of the inner lid only;

FIG. 11 is a front view of the outer lid only;

FIG. 12 is a rear view of the outer lid only; and,

FIG. 13 is a perspective view showing the outer lid and the inner lid open but not nested with each other.
